CLAIM

The ornamental design for a molded shell stack chair, as shown and described.

DESCRIPTION

FIG. 1 is a perspective view of the chair showing the new design.

FIG. 2 is a front elevational view thereof.

FIG. 3 is a side elevational view thereof, the opposite side being a mirror image.

FIG. 4 is a rear elevational view thereof.

FIG. 5 is a plan view thereof.

The design is characterized by the specifically configured unitized seat and backrest unit as best illustrated in FIGS. 1, 2 and 5.

Fig. 1.**Fig. 2.****Fig. 3.****Fig.4.****Fig.5.**
